Primary Examiner — Karen S Acker*Assistant Examiner* — Omeed Agilee(74) *Attorney, Agent, or Firm* — Dilworth IP, LLC(57) **CLAIM**

The ornamental design for a salad spinner, substantially as shown and described.

DESCRIPTION

FIG. 1 is a perspective view of the body of the salad spinner showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom view thereof.

The broken lines in the drawings depict portions of the salad spinner that form no part of the claimed design.
